COMBINATION GAS AND OIL BURNER AND
CONTROL THEREFOR

Cyril Charles Young, Kansas City, Mo.

Application September 1, 1948, Serial No. 47,319

18 Claims. (Cl. 158—11)

1

This invention relates to a combination oil and gas burner unit particularly adapted for domestic or industrial heating purposes.

In my copending applications, Serial Nos. 764,697 and 764,698, filed July 30, 1947, there is disclosed and claimed a novel combination gas and oil burner unit and control system therefor which will permit a heating plant to be efficiently operated either by an oil fuel or by a gas fuel, such as is derived from the ordinary city gas main. This type of burner unit has the advantage that for moderate outdoor temperatures, the heating of the building or residence in which the unit is installed may be accomplished solely by a gas fuel. However, upon the occurrence of extreme weather conditions, the unit may be operated to burn the oil fuel and adequately supply the required amount of heat without constituting an excessive demand upon the city gas supply. Under present day conditions wherein the supply of gas is necessarily limited due to the overwhelming demand therefor, such a combined unit has very remarkable advantages from the standpoint of reducing the peak load requirements of a city gas system.

Specifically, this application relates to certain improvements both in the burner construction and the control therefor over the arrangements disclosed in my above identified copending applications. One feature of this invention is the incorporation of an air blower in the burner unit to supply a pressured stream of air to support the combustion of the oil fuel. In accordance with this invention, such pressured stream of air is conveniently supplied through the same conduit that supplies the combustible gas and air mixture for the main burner gas flame.

Still another feature of this invention is the provision of an improved control arrangement for a combination gas and oil burner unit characterized by the incorporation therein of certain interlocking circuits between the valves controlling the supply of oil and gas fuel to the burner unit, to insure that under no conditions of operation will both the main gas burner and the oil burner be in concurrent operation, which would tend to produce an excessive heating of the furnace unit so as to involve the possibility of damage thereto.

This improved control circuit also includes interlocking arrangements for insuring that the blower which supplies a stream of pressured air to support the combustion of the oil fuel through the same conduit as the combustible gas and air mixture for the main gas burner flame is sup-

2

plied, will not be operated at any time when the burner is operating on the gas cycle, furthermore, to insure that such blower will be in operation at all times when the burner is operated on the oil cycle, and lastly, to insure the shut down of the burner in the event that a failure of the blower motor occurs while the burner is operating on the oil cycle.

Accordingly, it is an object of this invention to provide an improved combination gas and oil burner and control circuit therefor.

Another object of this invention is to provide an unusually simplified arrangement for supplying a stream of pressured air to a combination oil and gas burner to support the combustion of oil fuel therein and characterized by the utilization of a common conduit for such air stream and for the combustible gas and air mixture when the burner is operating on its gas cycle.

Still another object of this invention is to provide an improved control system for a combination oil and gas burner which will insure that the burner will never be operated with both fuels being supplied thereto concurrently, and furthermore, to effect the shutdown of the unit in the event of the failure of any of the essential components thereof, such as the pilot flame or the blower for supplying the pressured air stream to support the combustion of the oil fuel.

The specific nature of this invention, as well as other objects and advantages thereof will become apparent to those skilled in the art from the following detailed description of the annexed sheets of drawings which by way of preferred example only, illustrate one specific embodiment of the invention.

On the drawings:

Figure 1 is a vertical sectional view of the combustion chamber portions of a combination gas and oil burner constructed in accordance with this invention;

Figure 2 is a vertical sectional view of the remaining portions of the combination gas and oil burner unit, showing particularly the arrangements for supplying main burner gas, vaporizer gas, and a stream of pressured air to the combustion chamber assemblage illustrated in Figure 1; and

Figure 3 is a schematic diagram of the electrical control system for a combination gas and oil burner.

As shown on the drawings:

As indicated above, this application constitutes certain improvements over the burner construction and control circuits disclosed in my above

referred to copending applications. Accordingly, the unmodified elements of the burner unit will not again be described in detail and reference should be had to my copending applications for a detailed description of all elements of the burner unit which have not been modified in accordance with this invention.

The numeral 1 indicates the combustion chamber of a furnace which is supported in a relatively elevated position on a hollow cylindrical casing 2. All of the combustion producing elements of the combination gas and oil burner unit embodying this invention may then be conveniently mounted within the confines of the casing 2 in generally symmetrical relationship with respect to the vertical axis of a fire box opening 1a provided in the bottom of the fire box or combustion chamber 1 of the furnace.

The combination burner unit embodies a base casting 10 of generally inverted, cup-shaped configuration having an annular base portion 11 and a depending cylindrical wall portion 12 integrally formed on the periphery of base portion 11. At spaced intervals around the periphery of wall portion 12, a plurality of supporting leg portions 13 are provided, each of which is further provided with a radially extending flange 14. The top surface of each of the flanges 14 is provided with a pair of circumferentially extending arcuate grooves 15 and 16 respectively, which are radially spaced from each other. Thus the groove 16 is formed on the peripheral edge of the flanges 14, while the groove 15 is formed in an intermediate portion of the flanges 14.

Base portion 11 of base casting 10 has a flared juncture with an integral, upstanding cylindrical hub portion 17 which defines a central bore 18. Within the bore 18 a vertical, tubular gas burning conduit or nozzle member 19 is positioned. The nozzle member 19 is of cylindrical exterior configuration and fits snugly within the hub portion 17. At its bottom portions, the nozzle member 19 connects with a horizontal conduit 20 which extends radially outwardly of the casing 2 to a vertical wall 4 and there connects with the discharge port 21a (Figure 2) of a blower housing 21. A sleeve 22 is inserted in the horizontal conduit 20 and the bore of such sleeve defines a Venturi nozzle 22a. A motor driven blower rotor 21b is disposed in conventional fashion within the blower housing 21 and, when the electrical motor 48 (Figure 3) driving the blower rotor 21b is energized, the rotor will operate to pump a pressured stream of air into nozzle 22a, hence through conduit 20 and nozzle member 19, and thus produce an upwardly directed air stream directed toward the combustion chamber 1 to support the combustion of vaporized oil fuel in a manner that will be described in more detail later.

In accordance with this invention, the conduit 20 is also employed to conduct a combustible mixture of gas and air to the vertical nozzle member 19 to supply the main burner gas flame when the combination burner unit is operated on its gas cycle. Such combustible mixture of gas and air may be produced by a conventional inspirator nozzle 23 which projects into the blower housing 21 at a point adjacent the outlet port 21a thereof. Gas is supplied to inspirator nozzle 23 through a conventional electrically operated valve unit 24 which in turn is connected to a gas main 25.

Adjacent to the central nozzle member 19, a conventional pilot flame unit 26 is provided which

is indicated in dotted lines in Figure 1. Also, a pilot flame thermal switch unit 27 of conventional construction is mounted adjacent to the pilot flame unit 26 and operates in conventional fashion to maintain a pair of switch contacts closed so long as the pilot flame is burning and to open such contacts in the event of failure of the pilot flame produced by the pilot flame unit 26. Pilot flame unit 26 is supplied with gas through a pipe 26a which connects to the gas main 25 at any desired point.

The innermost groove 15 provided in the radial flanges 14 of the base casting 10 supports a generally cylindrical shell 30 which is mounted thereon in upstanding relation. An annular gas burner element 31 of generally hollow, torus-like configuration is mounted on the top of shell 30 and in surrounding relationship to the upstanding hub portion 17 of the base casting 10, hence in surrounding relationship to the mouth of the upstanding nozzle member 19. Burner element 31 is provided with two axially spaced sets of a plurality of gas burner jets 32 extending around its inner periphery and respectively directed angularly upwardly and downwardly toward the axis of the base casting 10. Each of the jets 32 communicates with the hollow bore 33 of the gas burner element 31 and a supply pipe 34 provides a combustible mixture of gas and air to the hollow portion 33. Supply pipe 34 in turn connects with a mixing nozzle 28 mounted on wall 4 (Figure 2) and gas is supplied to the mixing nozzle 28 by a conventional jet 29 which is connected to the gas main 25 through a pipe 29a and an electrically operated valve 70. When the valve 70 is in its open position, two axially spaced rings of gas flames are produced by the torus-like burner element 31, which will hereafter be referred to as the vaporizer burner.

Vaporizer burner 31 is further provided with a radially inwardly extending ledge 35 extending around its inner circumference. A ring 35a of heat insulating material rests upon such ledge and, in turn, is utilized to support an annular vaporizing pan or tray 36, which has an outwardly turned edge 37 engaging the ring 35a. Vaporizing tray 36 may be of any desired configuration and preferably is provided with a depressed base portion 36a so as to permit a substantial quantity of fuel oil to be collected in the vaporizer tray without danger of spilling therefrom. It will be noted that the tray 36 is thus supported intermediate the two rings of flame produced by the vaporizer burner 31, and hence the tray 36 will be rapidly heated to a high temperature. The insulating ring 35a sealingly mounts the tray 36 without substantial transfer of heat from the hot vaporizer tray to the relatively cool vaporizer burner.

To further amplify the heating effects of the gas jets of the vaporizer burner 31, a pair of refractory rings 38 and 39 are respectively mounted in axially spaced relationship below and above the vaporizer tray 36. Thus the bottom refractory ring 38 may be conveniently supported upon the top surface of the base portion 11 of the base casting 10.

The upper refractory element 39 is supported in depending relationship from an annular support plate or cover 40, which in turn rests upon the base portion 42 of an inverted, generally cup-shaped housing 41. Housing 41 is in turn supported in the peripheral groove 16 in the radial flanges 14 of the base casting 10. The plate 40 defines an inverted annular trough 44

which surrounds a central aperture 45 which is generally concentric with the axis of the base casting 10. The refractory elements are secured to the cover plate 40 in any convenient manner, such as is described in detail in my copending applications Serial Nos. 764,697 and 764,698, filed July 30, 1947. To further facilitate the heating of the vaporizer tray 36, the opposed surfaces of refractory elements 38 and 39 are preferably provided with a plurality of spaced refractory points 56.

The cover plate 40 is provided with an aperture 49 which is alignable with an aperture 46 in the upper refractory elements 39. Hence a passage is provided through plate 40 and refractory element 39 directly overlying the vaporizing tray 36, and this passage is employed to supply a limited flow of fuel oil to the vaporizing tray 36 when it is desired to burn fuel oil in the combined burner unit.

A drip type nozzle 50 is positioned directly above the aperture 49 and is connected to a suitable source of fuel oil through a pipe 51 and an electrically operated valve 47 (Figure 2). To protect the drip nozzle 50 from the high temperatures developed within the burner unit and to effect the feeding of the fuel oil to the vaporizing tray 36 without carbonization, the nozzle 50 and the supply pipe 51 are preferably encased within a sheet metal conduit 54 which extends to wall 4 and is open to atmosphere so as to permit a flow of cooling air to be continuously inducted through such conduit. Such conduit 54 not only provides additional air for combustion of the gas and oil within the burner, but also effectively maintains the drip nozzle 50 at a sufficiently low temperature that carbonization of fuel oil thereon is prevented. Conduit 54 is supported by a clamp 55 on an upstanding integral pedestal 56 formed on the cup-shaped housing 41.

From the foregoing description, it is apparent that whenever fuel oil is supplied to the vaporizing tray 36 through the energization of valve 47 to its open position, such fuel oil will be rapidly evaporated due to the high temperature of the tray and its location within the high temperature zone between the refractory elements 38 and 39. If the blower motor 48 is concurrently energized, a large volume stream of air will be produced which passes upwardly through the central opening in the annular vaporizer tray 36 and provides adequate air to support the combustion of the vaporized fuel oil. The temperature of the vaporizing zone is maintained sufficiently high to insure the rapid vaporization of fuel oil supplied thereto and, while some "cracking" of fuel oil occurs, any resulting combustibles are completely consumed, due to the high temperature of the vaporization zone and the presence of adequate oxygen. Any ash or non-combustibles deposited in the tray 36 are also swept into the air stream by the induced air flow produced around both the upper and lower faces of the burner tray 36. Hence it is assured that the vaporizer tray remains clean.

To effect an intimate mixture of the fuel oil vapors and the combustion supporting air stream, a mixing nozzle 60 is provided of generally Venturi configuration. Nozzle 60 is supported by a plurality of radially extending arms 61 upon nuts 62, which are in turn adjustably positioned on threaded studs 63 mounted in upstanding relationship on the base portion of the inverted cup-shaped housing 41. Hence the axial position of

the mixer nozzle 60 with respect to the opening 45 in the vaporizer cover 40 may be conveniently adjusted. Furthermore, it should be noted that nozzle 60 is axially spaced with respect to the plate 40 and is also of smaller diameter than the firebox opening 1a, so that additional flow of combustion supporting air into the combustion chamber is permitted by the resulting opening.

When the unit is properly adjusted and the optimum axial position of nozzle 60 determined, a thorough mixing action of fuel oil vapors and combustion supporting air occurs in the throat of the nozzle 60 and the burning of the combustible mixture is initiated before the mixture passes out of the end of the nozzle and into the combustion chamber 1. Preferably a target or flame spreader 3 is mounted in chamber 1 in conventional fashion.

The aforescribed arrangement permits high efficiency combustion to be obtained when the burner unit is operating on either its gas or oil cycle. The pilot flame produced by the pilot flame unit 23 is, of course, always in operation. When operating on the gas cycle, the motor 48 is deenergized and the valves 47 and 70 which respectively control the flow of oil to the vaporizing tray and the flow of gas to the vaporizer burner 31 are closed. Gas is supplied through the main gas valve 24 and adequate amounts of air necessary to support combustion are supplied by natural draft through the burner unit. When operating on the oil cycle, the main gas valve 24 is actuated to its closed position and the oil valve 47 and the vaporizer gas valve 70 are actuated to their open position and the blower rotor 21b is rotated.

Referring now to Figure 3, there is disclosed a control circuit embodying this invention for selectively controlling the energization of the main gas valve 24, vaporizer gas valve 70, oil valve 47, and blower motor 48. It is, of course, to be understood that the initiation of operation of the burner unit on either its gas burning or oil burning cycle may be automatically controlled in any desired manner and the particular arrangement for cycle selection shown in Figure 3 corresponds identically to that disclosed in my above referred to copending application Serial No. 764,698 wherein the selection of the gas or oil burning cycle is controlled by an outdoor thermostat 71 and the intermittent operation of the burner on the selected cycle is controlled by a room thermostat 72. The control circuit may be operated from any suitable source of power indicated as line terminals L1 and L2 and, if such source is of the alternating current type, may be stepped down to a suitable voltage by transformer 73.

The outdoor thermostat 71 is preferably of the snap action type wherein the switch blade 71a of the thermostat selectively engages either the contact G or a contact O depending upon whether or not the outside temperature is above or below a predetermined value. For purposes of illustration, it will be assumed that the outdoor thermostat 71 will have its switch blade 71a bridged across its neutral terminal N to the terminal G for all outdoor temperatures above a predetermined value and will have the switch blade 71a bridged across the neutral terminal N and the terminal O for all outdoor temperatures below such a predetermined value. The shifting of the switch blade 71a between the terminal G and the terminal O then effects the operation of the burner unit respectively on its gas and its

oil burning cycles in a manner to be described.

The indoor thermostat 72 may be of any conventional type and has been illustrated as of the well known three wire type, including a heating element 72b and a pair of contacts 72a which are closed whenever the room temperature is below a predetermined value and are opened whenever the room temperature exceeds a predetermined value.

The vaporizer gas valve 70 may be of any conventional electrically operated construction and for illustrative purposes is shown as a solenoid controlled type.

Main gas valve 24 is an electrically operated valve controlled by a conventional solenoid unit. Associated with main gas valve 24 is a circuit interlocking arrangement comprising a pair of contacts 24a and an actuator means cooperating with the stem of the main gas valve 24. When main gas valve 24 is closed, contacts 24a are closed and the control circuit to oil valve 47 is complete. But, regardless of how main gas valve 24 is opened, whether it be opened automatically by electrical means, manually or whether it be jammed open because of mechanical failure, the actuator means will operate to open contacts 24a thereby breaking the electrical control circuit to oil valve 47. This safety feature precludes simultaneous entry of the two different fuel media into the burner unit.

The oil valve 47 preferably incorporates a conventional delay action or time lag device so as to impart a suitable time delay characteristic in its operation, i. e., it will not initiate the flow of fuel oil to the burner unit until a substantial predetermined interval after its original energization and conversely, will continue to supply fuel oil to the burner unit for a limited period after its deenergization. Electrically operated fuel oil valve 47 may constitute any one of several well known forms and for illustrative purposes has been shown as comprising a heater type valve including an electrical heater 47a, which is the electrically energized element of the valve, and a time lag device which in this embodiment includes a bimetallic element 47b which operates an actuating bar 47c when heated by the heater element 47a. Actuating bar 47c cooperates with a pair of interlocking switches 74 and 75 and the stem 47d of the fuel oil valve 47 to actuate such elements in a predetermined sequence, both upon the energization of the fuel oil valve 47 and upon the deenergization thereof. As schematically indicated in Figure 3, the desired sequence of operation is that a short time after the original energization of heater element 47a, the actuating bar 47c effects the opening of the contacts of switch 74 and the closing of the contacts of switch 75. After a still further time interval, the actuating bar 47c engages the stem 47d of the valve to open the valve to permit fuel oil to be supplied to the burner unit. Upon deenergization of the heater element 47a, the sequence of operation is reversed. The valve stem 47d is first released to its closed position and then after a predetermined time delay, the switch 75 is actuated to its open contact position while the switch 74 is actuated to its closed contact position.

Referring particularly to that portion of the circuit represented by the heavy black lines of Figure 3, it will be seen that the vaporizer valve 70 and the blower motor 48 are concurrently energized by the closing of the normally open contacts of the switch 75 subsequent to the en-

ergization of the heater coil 47a of the electrically operated oil valve 47. Hence, it is assured that the vaporizer gas valve 70 will be opened and supplying gas to the vaporizer burner 31 to heat the vaporizer tray 36 to suitable temperature and that the blower 21b will operate before any fuel oil is supplied through the valve 47 to the vaporizing tray 36. The time delay incorporated in the mechanism of the electrically operated oil valve 47 insures that oil will not be supplied to the vaporizing tray 36 until proper combustion conditions are attained.

At the same time the opening of the contacts of the normally closed switch 74, which will be seen to be connected in the energization circuit of the main gas valve 24 insures that the main gas valve 24 will remain deenergized and thus in its closed position. Accordingly, irrespective of other conditions in the circuit, the main gas valve 24 cannot be opened when the fuel oil valve 47 has been energized.

It should be further noted that if oil valve 47 is operated manually, as might well occur under operating conditions subsequent to an electrical current interruption, or if oil valve 47 is jammed open because of mechanical difficulties, valve stem 47d operates to open switch 74 thereby breaking the electrical control circuit to main gas valve 24. Inasmuch as the contacts 24a, which are associated with the main gas valve 24, are connected in series circuit with the heater elements 47a of the electrically operated fuel oil valve 47, the electrical control circuit between the fuel oil valve 47 and the main gas valve 24 is completely interlocked so irrespective of how one of the valves may have been opened, simultaneous operation by electrical means of both main gas valve 24 and oil valve 47 is precluded.

Normally closed contacts of a safety switch unit 76 associated with the blower 21b are also connected in the energizing circuit of the heater element 47a of the electrically operated valve 47. The switch 76 is of well known construction and is associated with the blower rotor 21b in such manner that so long as the blower rotor 21b is functioning normally, the contacts of switch 76 will remain closed. However, when a failure of the blower rotor 21b occurs, the switch 76 will open and result in the deenergization of the heater coil 47a of the fuel oil valve 47 and hence a closing of the fuel oil valve 47. In addition, contacts of the pilot flame responsive switch 27 are connected in the common lead 77 which is included in the energizing circuits of both the fuel oil valve 47 and the main gas valve 24. Accordingly, upon the failure of the pilot flame, the pilot flame switch 27 will open its contacts and prevent the operation of either the fuel oil valve 47 or the main gas valve 24.

The cooperation of the outdoor thermostat 71 and the indoor thermostat 72 with the remaining elements of the control circuit is identical to that employed in my above referred to copending applications. When the outdoor temperatures are below a predetermined value, circuit connections are completed as illustrated in Figure 3 through the terminal O of the outdoor thermostat 71 to energize the heater element 47a of the electrically operated fuel oil valve 47 whenever the indoor thermostat 72 is calling for heat by closing of its contacts. When the outdoor temperature is above such predetermined value the outdoor thermostat 71 completes an energization circuit through its contact G for the main gas valve 24

whenever the indoor thermostat 72 calls for heat by the closing of its contacts 72a.

From the foregoing description, it is apparent that this invention provides not only an improved and simplified construction of a combined gas and oil burner unit through the utilization of a common conduit for the supply of the pressured air stream for the burner while operating on the oil cycle and for the supply of the combustible mixture of gas and air when operating on the gas cycle, but the described control circuit completely prevents the concurrent supply of both main burner gas and fuel oil to the burner unit under any conditions of operation. Furthermore, the interlocking of the gas and oil valves with the pilot flame switch and the blower protector switch insures that fuel will not be supplied to the burner unit unless proper combustion conditions are first produced in the burner unit.

It will, of course, be understood that various details of construction may be modified through a wide range without departing from the principles of this invention and it is, therefore, not the purpose to limit the patent granted hereon otherwise than necessitated by the scope of the appended claims.

I claim as my invention:

1. A control system for a combined gas and oil burning heater comprising, in combination, a first electrically operated valve means controlling the supply of gas to said heater, a second electrically operated valve means controlling the supply of oil to said heater, a thermostat, and circuit means controlled by said thermostat for selectively energizing said first or second valve means, said circuit means including a pair of interlocking switches respectively operated to open position by energization of said first and second valve means, means connecting the interlocking switch operated by said first valve means in circuit with said second valve means, and means connecting the interlocking switch operated by said second valve means in circuit with said first valve means, whereby only oil or only gas may be supplied to said heater.

2. A control system for a combined gas and oil burning heater comprising, in combination, a first electrically operated valve means controlling the supply of gas to said heater, a second electrically operated valve means controlling the supply of oil to said heater, a thermostat, and circuit means controlled by said thermostat for selectively energizing said first or second valve means, said circuit means including switch means associated with each of said first and second valve means and actuatable thereby for interlocking the energization circuit of said first and second valve means to prevent concurrent energization of both valve means, whereby only oil or only gas may be supplied to said heater at any one time.

3. In combination, a gas and oil burning heater, a first electrically operated valve means controlling the supply of gas to said heater, a second electrically operated valve means controlling the supply of oil to said heater, a third electrically operated valve means for controlling the supply of an oil vaporizing medium to said heater, a thermostat, circuit means controlled by said thermostat for selectively energizing either said first valve means or said second and third valve means concurrently, said circuit means including a pair of interlocking switches respectively operable to open position by energization of said first and second valve means, means connecting the interlocking switch operated by said

5 first valve means in circuit with said second valve means, and means connecting the interlocking switch operated by said second valve means in circuit with said first valve means, whereby only oil or only gas may be supplied to said heater at any one time.

4. A control system for a combined gas and oil burning heater comprising, in combination, a first electrically operated valve means controlling the supply of gas to said heater, a second electrically operated valve means controlling the supply of oil to said heater, a thermostat, and circuit means controlled by said thermostat for selectively energizing said first or second valve means, an electrically operated blower arranged to produce a stream of air to support the combustion of the oil, switch means responsive to operation of said second valve means for energizing said blower, and switch means actuatable in response to operation of said first and second valve means for interlocking the energization circuits of said first and second valve means to prevent concurrent energization of both valve means, whereby only oil or only gas may be supplied to said heater at any one time.

5. In combination a gas and oil burning heater, a first electrically operated valve means controlling the supply of gas to said heater, a second electrically operated valve means controlling the supply of oil to said heater, a third electrically operated valve means controlling the supply of an oil vaporizing medium to said heater, an electrically driven blower arranged to produce a stream of air to support combustion of the oil, a thermostat, circuit means controlled by said thermostat for selectively energizing either said first valve means or said second valve means, and switch means associated with said second valve means for energizing both said third valve means and said blower when said second valve means is energized.

6. In combination a gas and oil burning heater, a first electrically operated valve means controlling the supply of gas to said heater, a second electrically operated valve means controlling the supply of oil to said heater, a third electrically operated valve means controlling the supply of an oil vaporizing medium to said heater, an electrically driven blower arranged to produce a stream of air to support combustion of the oil,

45 a thermostat, circuit means controlled by said thermostat for selectively energizing either said first valve means or said second valve means, and switch means associated with said second valve means for energizing both said third valve means and said blower when said second valve means is energized, a pair of interlocking switches respectively operated to open position by energization of said first and second valve means, means connecting the interlocking switch operated by said first valve means in circuit with said second valve means, and means connecting the interlocking switch operated by said second valve means in circuit with said first valve means, whereby only oil or only gas may be supplied to said heater at any one time.

7. In combination, a gas and oil burning heater, a first electrically operated valve means controlling the supply of gas to said heater, a second electrically operated valve means controlling the supply of oil to said heater, a third electrically operated valve means controlling the supply of an oil vaporizing medium to said heater, an electrically driven blower arranged to produce a stream of air to support combustion of the oil,

11

a thermostat, circuit means controlled by said thermostat for selectively energizing either said first valve means or said second valve means, and switch means associated with said second valve means for energizing both said third valve means and said blower when said second valve means is energized, and switch means responsive to operation of either said first or second valve means for interlocking the energization circuits of said first and second valve means to prevent concurrent energization of both valve means.

8. In combination, a heater having means for burning a gas fuel and vaporizing means for burning an oil fuel, a first electrically operated valve means controlling the supply of gas to said heater, a second electrically operated valve means for controlling the supply of oil to said heater, said second electrically operated valve means including means for delaying opening and closing movements of the valve in response to energization and deenergization respectively, a third electrically operated valve means for controlling the supply of gas for heating said vaporizing means, an electrically driven blower, switch means associated with said second valve means for energizing said third valve means and said blower subsequent to the energization of said second valve means but preceding the opening of said second valve means to supply oil to said heater, a thermostat, and circuit means controlled by said thermostat to selectively energize either said first valve means or said second valve means.

9. In combination, a heater having means for burning a gas fuel and vaporizing means for burning an oil fuel, a first electrically operated valve means controlling the supply of gas to said heater, a second electrically operated valve means for controlling the supply of oil to said heater, said second electrically operated valve means including means for delaying opening and closing movements of the valve in response to energization and deenergization respectively, a third electrically operated valve means for controlling the supply of gas for heating said vaporizing means, an electrically driven blower, switch means associated with said second valve means for energizing said third valve means and said blower subsequent to the energization of said second valve means but preceding the opening of said second valve means to supply oil to said heater, a thermostat, and circuit means controlled by said thermostat to selectively energize said first valve means or said second valve means, and means for interlocking the energization circuits of said first and second valve means to prevent concurrent energization of both valve means.

10. In combination, a heater having means for burning a gas fuel and vaporizing means for burning an oil fuel, a first electrically operated valve means controlling the supply of gas to said heater, a second electrically operated valve means for controlling the supply of oil to said heater, said second electrically operated valve means including means for delaying opening and closing movements of the valve in response to energization and deenergization respectively, a third electrically operated valve means for controlling the supply of gas for heating said vaporizing means, an electrically driven blower, switch means associated with said second valve means for energizing said third valve means and said blower subsequent to the energization of said second valve means but preceding the opening

12

of said second valve means to supply oil to said heater, a thermostat, and circuit means controlled by said thermostat to selectively energize either said first valve means or said second valve means, a pair of interlocking switches respectively operated to open position by energization of said first and second valve means, means connecting the interlocking switch operated by said first valve means in circuit with said second valve means, means connecting the interlocking switch operated by said second valve means in circuit with said first valve means, thereby preventing concurrent operation of said first and second valve means.

15 11. The combination defined in claim 8 plus means for producing a pilot flame, and wherein said circuit means includes a normally closed switch operable to open contact position upon failure of said pilot flame, thereby cutting off all fuel supply to said heater.

12. The combination defined in claim 9 plus means for producing a pilot flame, and wherein said circuit means includes a normally closed switch operable to open contact position upon 25 failure of said pilot flame, thereby cutting off all fuel supply to said heater.

13. The combination defined in claim 8 wherein said circuit means includes a normally closed switch operable to open contact position upon 30 failure of said blower, thereby interrupting all fuel supply to said heater.

14. The combination defined in claim 9 wherein said circuit means includes a normally closed switch operable to open contact position upon 35 failure of said blower, thereby interrupting all fuel supply to said heater.

15. The combination defined in claim 8 plus means for producing a pilot flame, and a pair of normally closed switch devices series connected 40 in said circuit means, one of said switch devices being operable to open contact position by failure of said pilot flame and the other of said switch devices being operable to open contact position upon failure of said blower, thereby interrupting the supply of fuel to said burner upon 45 operation of said switch devices.

16. A gas or oil burning heater comprising an annular vaporizing tray, means including a first valve for supplying oil to said tray, means for maintaining said tray at a vaporizing temperature, a gas burning nozzle arranged to project a gas flame through the central opening of said vaporizing tray, a conduit connected to said nozzle, a blower operatively connected to the other end of said conduit to produce an air stream discharge from said gas burning nozzle, means including a second valve for injecting a stream of gas into said conduit, and means for energizing said blower only when said first valve means is operated to supply oil to the heater.

60 17. A control system for a combined gas and oil burning heater comprising, in combination, a first electrically operated valve means controlling the supply of gas to said heater, a second electrically operated valve means controlling the supply of oil to said heater, a thermostat, an electric circuit controlled by said thermostat, means within said circuit responsive to said thermostat to selectively actuate said first and second valve means, said circuit means including a pair of interlocking switches, each being respectively operable to an open position whenever either one of said first and second valve means is in an open position, and additional circuit means associated 65 with said pair of interlocking switches for respec-

75

13

tively interconnecting said switches in circuit between said first and second valve means whereby when either of said first and second valve means is in an open position the other of said first and second valve means cannot be energized to an open position.

18. In combination, a gas and oil burning heater, a first electrically operated valve means controlling the supply of gas to said heater, a second electrically operated valve means controlling the supply oil to said heater, a third electrically operated valve means controlling the supply of gas to an oil atomizer burner within said heater, a thermostat, circuit means controlled by said thermostat for selectively energizing either said first valve means or said second and third valve means concurrently, said circuit means including a pair of interlocking switches respectively operable to open position when either of said first and second valve means is opened, means respectively interconnecting said interlocking switches and said first and second valve

5

14

means in circuit, whereby only gas may be supplied to said heater or only oil may be supplied to said heater concurrently with the gas being supplied to said oil atomizer burner at any time.

CYRIL CHARLES YOUNG.
